UNITED STATES PATENT OFFICE

LYMAN C. HUFF, OF CHICAGO, ILLINOIS, ASSIGNOR TO UNIVERSAL OIL PRODUCTS COMPANY, OF CHICAGO, ILLINOIS, A CORPORATION OF SOUTH DAKOTA

APPARATUS FOR REMOVING CARBONACEOUS DEPOSITS FROM OIL APPARATUS

Application filed July 22, 1925, Serial No. 45,363. Renewed February 2, 1929.

This invention relates to improvements in the apparatus for removing carbon material that has deposited in the enlarged reaction chamber of a tube and drum oil cracking apparatus.

One of the objects of the invention is to provide means for breaking up the mass of deposited carbon so that it may be easily removed from the chamber. It is also an object of the invention to so construct the apparatus that it may be easily positioned in the reaction chamber and readily withdrawn therefrom.

In the drawings,—

15 Figure 1 is a sectional view in side elevation of an enlarged vertical reaction chamber showing my invention applied thereto.

Fig. 2 is a horizontal sectional view of the structure shown in Fig. 1.

20 The reference character 1 designates an enlarged vertical reaction chamber of a type in general commercial use with tube and drum cracking processes. This reaction chamber 1 is provided with a heated oil inlet line 2 controlled by suitable valve 3 as well as with a vapor outlet line 4 controlled by valve 5 through which vapors evolved from the heated oil introduced to the chamber pass to a dephlegmator or condenser (not shown).

25 The reaction chamber may be provided with the usual manhole covers at the top and bottom as indicated at 6 and 7.

30 Coming more particularly to the novel feature of my invention, I provide annular rows 35 of hooks or suitable fastening devices around the top of the reaction chamber on the interior thereof as indicated at 8 and 9, the inner row 8 being preferably positioned relatively close to the upper opening of the chamber

40 while the outer row 9 may be disposed at a substantial distance therefrom. I suspend from these annular rows of hooks a single continuous flexible element such as a metallic chain or cable. In the drawings I have 45 shown a chain 10. It will, of course, be understood that a cable may be employed. The end 11 of this chain is releasably supported by one of the hooks or fastening devices in the row 8. The chain passes down to 50 a point near the bottom of the chamber and is

thence doubled back to a second hook in the row 8, passed to a third hook in such row and again looped to a point adjacent the bottom of the chamber, this operation being continued until the chain has been releasably fastened, as for example, by light gauge wire as shown at 12, to all of the hooks in the row 8. The chain is thence led to the row 9 and similarly secured to all of the hooks or fastening devices of that row. The free end of 60 the chain shown at 13 is shown as positioned at the bottom of the chamber so that it will be readily accessible when the cover 7 is opened.

65 It will be readily apparent that the chain 10 can be withdrawn either from the top of the chamber or from the bottom of the chamber. If desired, the end 11 of the chain can be suitably connected to a winch and the chain withdrawn through the top of the 70 chamber. If it is more convenient the chain can be withdrawn from the bottom of the chamber by securing the end 13 to a suitable winch mechanism.

75 One of the great difficulties incident to employing vertical reaction chambers is that the carbon deposits to a considerable depth in the chamber and is exceedingly difficult to remove. The alternate looping at the bottom and top of the chamber of the chain 10 80 in my improved apparatus causes this mass of deposited carbon to be very completely broken up when the chain is withdrawn. The positioning of all of the fastening elements by which the chain is secured at the top of a 85 chamber permits of ready application of the chain to an empty chamber preparatory to commencing a run.

What I claim as my invention is:

1. An apparatus for disrupting and removing carbon from an enlarged reaction chamber in an oil cracking apparatus, comprising a single continuous flexible element releasably suspended intermediate its ends from a plurality of spaced points at the top 90 of the chamber different intermediate portions of said flexible element being vertically disposed throughout the entire depth of deposited carbon in the reaction chamber, said flexible element adapted to be withdrawn 100

from the chamber to disrupt the carbon deposited therein.

2. An apparatus for disrupting and removing carbon from an enlarged reaction chamber in an oil cracking apparatus, comprising a single continuous flexible element releasably suspended intermediate its ends from a plurality of spaced points at the top of the chamber and different intermediate sections of said flexible element being disposed throughout the entire depth of deposited carbon in the reaction chamber, and means for permitting the withdrawal of said flexible element from said chamber to disrupt the carbon deposited therein.

3. An apparatus for disrupting and removing carbon from an enlarged reaction chamber in an oil cracking apparatus, comprising a single continuous flexible element releasably suspended intermediate its ends from a plurality of spaced points at the top of the chamber, different portions of said flexible element being disposed vertically through the mass of deposited carbon in the reaction chamber, said flexible element adapted to be withdrawn from the chamber to disrupt the carbon deposited therein.
